RUBBING DEVICE

Ottmar A. Kehle, West Los Angeles, Calif., assignor, by mesne assignments, to Sterling Tool Products Company

Application October 24, 1939, Serial No. 300,969

6 Claims. (Cl. 51—170)

My invention has to do with improvements in rubbing machines such, for instance, as are used in sanding or buffing operations.

In particular, it is an object of my invention to provide a machine of this character having a propelling unit and a buffing pad element and in which the propelling unit is housed within the pad element.

Another object is to provide novel, efficient and durable means for connecting the working face of the pad to the remaining elements.

Another object is to provide a device of this character wherein the parts are so assembled and mounted as to reduce to a minimum the amount of vibration transmitted to the hand of the operator.

Another object is to provide in such a device a construction which is extremely quiet in operation.

Another object is to provide a rubbing device in which the rubbing pad is so connected to the propelling element as to provide a smooth reciprocation of the working element in a relatively constant plane.

Another object is to provide a device which is extremely durable, easy to assemble and disassemble and which is economical of manufacture.

The invention with still further objects and resultant advantages thereof, and the particular construction, combinations and arrangements of parts comprising the same, will be understood from the hereinafter contained detailed description when considered in connection with the accompanying drawing forming a part hereof and illustrating one embodiment of the invention. In the drawing:

Fig. 1 is a plan view;

Fig. 2 is a longitudinal section on line 2—2 of Fig. 1, with some parts being shown in elevation;

Fig. 3 is an end view taken on line 3—3 of Fig. 2, with some parts being shown in cross-section; and

Fig. 4 is a horizontal section on line 4—4 of Fig. 2.

Referring now to the drawing, I show a top resilient pad 5, preferably composed of rubber, faced at its underside by a metal plate 6 which has downwardly extending side flanges 6a, which metal plate is upwardly bowed at its center 6b to provide space for the reciprocating element to be later described. A plurality of holes 8 (preferably four in number) extend vertically through pad 5, and concentric with each of said holes there is a hole 9 of relatively small diameter through plate 6. As best shown in Fig. 3, pad 5

5 has a downwardly depending skirt portion 5a at each of its sides. Extending longitudinally in and adjacent one side of pad 5 there is a rectangular recess 10 in which is mounted the valve operating lever to be later described.

10 A motor 15 of any suitable construction is secured to and suspended from plate 6 by means of screws 16 which pass through holes 8 and 9 and are threaded at their lower ends into holes in the top of the motor as shown, the sides of the motor being covered by flanges 6a. While no claim is here made to the particular construction of the motor element per se, I find that a fluid motor of the type generally described in my copending application Serial Number 280,118, filed June 20, 1939, is well suited for the purpose and inasmuch as reference may be made to that copending application for details of the working parts of the motor element, it will suffice here to state that it includes a block 15a having a longitudinal bore and piston (not shown), and extending vertically through the center of the piston member there is a power transmitting pin 17 which is reciprocated by the piston and which projects at its top end through the motor valve operating yoke 20 and carries a nut 21 at its top end. Yoke 20 is fulcrumed on a pin 22 carried by the motor block 15a and acts as a lever to engage and actuate the valve pin 25 controlling 20 the inlet and outlet of fluid to and from the respective ends of the piston. The top end of the pin 17 reciprocates along an elongated opening 26 provided through the top of the motor block and valve pin 25 reciprocates along an elongated opening 27 also provided through the top of the motor block. An air inlet 30 to the motor is provided through the side of the motor block, said inlet being accessible through an opening 29 in one of the side flanges 6a and being controlled by a valve 31 (Fig. 3) which is adapted to be moved off its seat 32 by stem 33, said inlet being adapted to receive a fluid supply hose 30a. Stem 33 is in turn manually actuated into valve opening position by the valve lever 34 which is 25 pivotally connected to pad plate 5 by pivot pin 35. A coil spring 36, which seats at its bottom against plug 37 threaded into the motor block, and at its top against valve 31, urges the valve into seating position.

30 Interposed between the top of the motor block and plate 6, I provide a pair of rubber shock absorbers 38 disposed one at each end of the elongated opening 26 in position to be contacted by the yoke 20 at each end of the piston stroke.

35 A pair of oppositely disposed, relatively thick

flexible webs 40, preferably of rubber, which are outwardly arched as shown in Fig. 2, are provided. The top end of each of these webs is provided with transverse spaced holes 41 into which project the respective lugs 42 carried by the motor block, said top ends of the webs being confined between the motor block and plate 6 by means of the screws 16. The lower ends of the webs are secured to the top plate 44 of a rubbing element to be described by means of rivets 48 and transverse clamping strips 45, said strips being downwardly bent at their ends as shown at 47 to resist lateral displacement of the webs.

A shoe 50 is secured to the plate 44 by means of rivets 53 passing through holes in its flanged portions 54, and into this shoe fits the enlarged end 17a of pin 17, one side of the shoe being open, as shown at 51, to pass the enlarged end 17a during assembling and disassembling. The lower pin end 17a is normally spaced from the bottom of the shoe to permit vertical movement of the pin end 17a within the shoe as the webs 40 are flexed. The top of the shoe has an inwardly extending flange portion 55 which overhangs the enlarged pin end 17a to prevent further upward movement of the pin with respect to the shoe after it reaches the uppermost position shown in Fig. 2.

A flexible cushion 60 is secured to plate 44 by having its socketed ends 51 fit over the respective ends of plate 44. Cushion 60 is preferably composed of rubber and has a dove-tailed recess 63 at its bottom into which is moulded a resilient pad 65 which is preferably of felt or the like. An abrasive or working sheet 70 is stretched over the bottom face of cushion 60 and pad 65, the respective ends of said sheet 70 being folded around the overhanging ends 60a and confined by being held against plate 44 by the overhanging ends 60a of cushion 60, the loose end of the working sheet 70 fitting into recesses 67 provided in the top face of cushion 60.

In operation, the longitudinal movement of the piston within the bore reciprocates its carried pin 17 which in turn transmits the reciprocating movement to the working face of the pad element while the operator holds the top plates 5 and 6 and the carried motor relatively stationary. The arched flexible webs 40 permit the rubbing pad element to be reciprocated without tending to raise the ends of the pad at and adjacent the ends of the stroke, thus maintaining the movement of the pad in a substantially constant plane, although, due to the flexibility of the working face of the pad itself, it is capable of flexing to follow a curved or uneven surface being worked upon.

In devices of the prior art, the motor is usually the topmost element, the pad being secured to or carried by the bottom of the motor. In such cases, if the top ends of the webs are firmly secured to the bottom of the motor, the webs are so relatively short that it requires considerable exertion on the part of the operator to hold the motor stationary and the short webs deteriorate rapidly due to the great stresses placed upon them by reciprocation of the working face of the pad. My invention has a distinct advantage over such devices inasmuch as in my device, wherein the pad element may be said to consist of the webs 40 and the rubbing element, the webs may be of substantially greater length and may be thicker and more durable. The flexing stress on any part of the webs is not very great, so that the top portion may be held stationary with 73

little effort and the webs are capable of long life, the operation being at the same time much smoother. Furthermore, since the thickness of the rubber webs is interposed between the top 5 of the motor and the top plates, the vibration transmitted to the hand of the operator is reduced to a minimum and the motor noises are materially damped because the motor is substantially housed within a rubber casing provided by the pad element.

While, in the foregoing description, I have resorted to various details of structure and association of parts, I wish it understood that I do not thereby confine my invention to such specific 15 details. Rather, various modifications and adaptations may be made within the broader scope of the invention as defined by the appended claims.

I claim:

20 1. A device of the class described comprising a rubbing element, a pair of flexible strips secured at their lower ends to the respective ends of the rubbing element and extending upwardly therefrom, a top plate, a motor secured to and suspended below said plate, the top ends of said flexible strips being secured between the motor and said plate, side flanges on said plate extending downwardly to cover the sides of the motor and means operatively connecting the motor to the rubbing element whereby to oscillate the latter.

25 2. The device of claim 1 which includes a resilient member mounted on said top plate and extending downwardly along the exterior surface of said side flanges of the top plate to provide a gripping surface.

30 3. A rubbing device including a pad element comprised of top and bottom portions spaced apart by flexible end walls, a motor secured to and suspended below the top portion, a power transmitting pin adapted to be oscillated by the 35 motor and projecting therebelow to oscillate the bottom portion of the pad element with respect to the motor, and a shoe secured to the bottom portion and opening upwardly to receive the lower end of said pin, the bottom end of said pin being normally spaced from the bottom of the shoe whereby to permit of vertical movement of the bottom portion of the pad element with respect to the top portion upon flexing of the end walls.

40 4. A rubbing device including a pad element comprised of top and bottom portions spaced apart by flexible end walls, a motor suspended below the top portion between said end walls, a power transmitting pin operatively connected at its top end to the motor and projecting downwardly therefrom, the lower end of said pin being headed, and a shoe secured to said bottom portion of the pad element and opening upwardly to receive said headed end of the pin, said shoe having an inwardly projecting top flange overhanging the headed end of the pin and a slotted side wall through which said headed end of the pin may be laterally inserted into and removed from the shoe.

45 5. A rubbing device including a pad element comprised of top and bottom portions spaced apart by flexible end walls, a motor secured to and suspended below the top portion, said motor having a reciprocating valve actuating pin projecting through an elongated slot in its top wall, resilient bumper members positioned between the top portion of the pad and the top of the motor and positioned one at each end

of said slot whereby to be contacted by said pin at the respective extremes of its movement along said slot, and means operatively connecting the motor to the lower portion of the pad whereby to move the latter with respect to the motor.

6. A rubbing device including a pad element comprised of top and bottom portions spaced apart by flexible end walls, said top portion being adapted to be held stationary with respect to the bottom portion, the top portion of said

5 pad element being comprised of a substantially rigid bottom plate and a resilient cover plate, a motor firmly secured to and suspended below the said rigid bottom plate whereby to be positioned between said end walls, the upper ends of said end walls being confined between the motor and said bottom plate, and means operatively connecting the motor to the bottom portion of the pad element whereby to move the latter with respect to the top portion.

OTTMAR A. KEHLE.
